Primary Examiner — Lauren D McVey(74) *Attorney, Agent, or Firm* — JCIP Global Inc.(57) **CLAIM**

The ornamental design for a display mount, as shown and described.

DESCRIPTION

FIG. 1 is a first perspective view of a display mount showing my new design;

FIG. 2 is a second perspective view of FIG. 1;

FIG. 3 is a front view of FIG. 1;

FIG. 4 is a rear view of FIG. 1;

FIG. 5 is a left side view of FIG. 1;

FIG. 6 is a right side view of FIG. 1;

FIG. 7 is a top view of FIG. 1;

FIG. 8 is a bottom view of FIG. 1;

FIG. 9 is a third perspective view of the display mount, wherein vertical brackets of the display mount are tilted; and,

FIG. 10 is a fourth perspective view of the display mount, wherein vertical brackets of the display mount are tilted in an alternate state.

The broken lines immediately adjacent to the claim depict the bounds of the claimed design, while all other broken lines are directed to the environment. The broken lines form no part of the claimed design.

1 Claim, 8 Drawing Sheets(56)
